UNITED STATES PATENT OFFICE.

GEORGE E. MARTIN, OF PHILADELPHIA, PENNSYLVANIA, ASSIGNOR TO THE PEDRICK AND AYER COMPANY, OF PLAINFIELD, NEW JERSEY.

RIVETING-MACHINE.

SPECIFICATION forming part of Letters Patent No. 733,497, dated July 14, 1903.

Application filed August 14, 1902. Serial No. 119,610. (No model.)

To all whom it may concern:

Be it known that I, GEORGE E. MARTIN, a citizen of the United States, residing at Philadelphia, in the county of Philadelphia and 5 State of Pennsylvania, have invented certain new and useful Improvements in Riveting-Machines, of which the following is a specification.

This invention relates to pneumatic riveting-machines in which a power cylinder and piston and a riveting cylinder and piston are employed that communicate by passages filled with a liquid and through which the maximum force from the power cylinder piston is 10 transmitted to the riveting cylinder and piston, combined with an auxiliary or minor cylinder and piston that communicates with the air-pressure independent of the power cylinder and piston and communicates with 15 the riveting cylinder and piston also by passages filled with a liquid for transmitting a lesser degree of force to bring the riveting-piston and connected riveting-die in contact with the rivet preliminary to the formation 20 of the rivet-head by the action of the power-piston.

The invention also embodies an automatic valve device that normally cuts off the communication between the liquid-chambers of 25 the power-piston and the minor cylinder. The valve is opened by the direct pressure of the power-transmitting liquid in the minor cylinder to permit its flow to the riveting-cylinder and by the direct air-pressure acting 30 upon its connected piston to permit its return to the minor cylinder.

In order that the invention may be readily understood, I will first describe the operation of the machine embodying it and illustrated 40 in the accompanying drawings, referring incidentally to the parts and constructive details that make up the structure, and subsequently will point out in the appended claim the novel characteristics of the invention.

In the drawings, Figure 1 represents a side elevation of the machine shown partly in section and with the operative parts in relative position at the extreme open stroke of the 45 riveting-plunger; Fig. 2, a plan view, partly in section, including the minor cylinder and

piston; Fig. 3, an end view in section through the valve-chamber; and Fig. 4 an enlarged view, partly in section, of the riveting-cylinder and piston and valve device in communication therewith and with passages leading to the minor cylinder and air-supply.

In the drawings, B is the framework, of the design usually adopted in portable machines of this class, having the power-cylinder A 60 and riveting-cylinder 5, with their communicating parts mounted upon one branch or arm of the framework and the anvil C upon the other branch.

In the relative positions of the parts as shown air-pressure is admitted from supply-pipe 1 through valve 2 to passage 3 into the push-back chamber 4 of cylinder 5 beneath the riveting-piston 6 and raises the piston to its normal vertical position, as shown. 70 This air-pressure is at the same time admitted to the annular air-chamber 7 in front of the power-piston head 8 through the port 9 and located at the rear end of the power-cylinder A. In this position of the valve 2 the exhaust-opening to the atmosphere 10 is open to the rear of the power-piston head 8 through the passage 11 and to the rear of the floating piston 15 of the minor cylinder 14 by the passage 16. The transmitting fluid fills the respective chambers 28 of the power-piston trunk and 13 of the minor cylinder 14 and all the intermediate passages communicating therewith, the floating piston 15 of the minor cylinder being thereby moved to its normal 85 starting-point, as shown. The operative parts are now in relative position for action. The valve 2, by means of the hand-lever O, is now set to register with the supply-pipe port and the passage 16, leading to the minor cylinder 14, and with the exhaust-opening 10 and passage 3, leading from the chamber 7 in front of the power-piston head 8 and from the push-back chamber 4 beneath the riveting-piston 6. The pressure being now applied solely to 90 the floating piston 15, the transmitting fluid in front of the same is forced through the pipe 18, passage 19, check-valve 20, and passage 21 to the chamber 22 above the riveting-piston 6 and forces the piston and its connected riveting-plunger 23 in contact with the rivet to be headed. During this preliminary

movement of the riveting-piston 6 all communication of the air-pressure with the power-piston is closed. In this preliminary movement of the piston 6 the air is expelled from 5 the chamber 4 beneath the same through pipe 3 and the exhaust-passage 10. At the same time the check-valve 20 is closed by the release of the air-pressure from beneath its connected piston 25 and the resilient action 10 of the connected spring 26. The valve 2 is now set to register the pressure-inlet 1 with the port 11, leading to the power-piston head 8, the air being discharged from its front port 9 and passage 3 to the exhaust-opening 10, 15 which is still open. The movement of the piston and trunk within the power-cylinder A forces the hollow fixed spindle 27 into the trunk fluid-chamber 28 of the piston, and by the displacement of the spindle the fluid is 20 forced through it into chamber 22, which intensifies the pressure upon the riveting-piston to form the rivet-head. Following the formation of the rivet-head the valve 2 is set to its first position, as shown in Fig. 1, and 25 the parts are returned to their normal position, as previously described, ready for another operation.

The main essential elements that comprise the machine herein referred to, consisting of 30 the power-cylinder with its chambered trunk-piston and coöperating fixed hollow spindle and the connected riveting cylinder and piston, together with the minor cylinder and its floating piston, and a valve device that normally closes the liquid communication between the minor cylinder and the power-piston chamber, are also included in a prior application for a patent, filed by me December 21, 1901, Serial No. 86,734, but embodied 35 therein in a different structural relation and coöperation. In the prior application referred to the minor cylinder is arranged parallel with and adjacent to the riveting-cylinder and the interposed valve device located 40 within the extremity of the riveting-cylinder. 45

In the present invention the minor cylinder is arranged parallel with the power-cylinder and the valve device arranged in the frame of the machine directly intermediate of the respective power-cylinders and the riveting-cylinder, this relative arrangement rendering the connections with all the fluid-chambers of the respective cylinders and the air chambers and passages short and direct, thereby effecting quick action through less travel 50 of the actuating fluids and producing a more compact and stronger construction with increased efficiency. 55

Having thus fully described my invention, what I herein claim, and desire to secure by Letters Patent, is—

In a riveting-machine, the combination of a frame, a power cylinder and piston for compressed air, a minor cylinder and floating piston for compressed air, and a riveting cylinder and piston, a valve for controlling the compressed air, a passage for conducting compressed air beneath the riveting-piston for returning the same, and provisions in virtue of which the power-piston and floating piston may act upon the riveting-piston through an interposed liquid medium, said provisions comprising independent passages from the two cylinders to the top of the riveting-cylinder, the passage from the minor cylinder 75 lying partly in the portion of the frame adjacent to the riveting-cylinder, and a check-valve for the purpose set forth in said portion of said passage in said portion of the frame, said check-valve being provided with 80 a motor-piston exposed to the pressure which returns the riveting-piston, substantially as described.

In testimony whereof I affix my signature in presence of two witnesses.

GEORGE E. MARTIN.
